[57] ABSTRACT

A structure such as a house provided with a support system supporting it in overhanging relation to a hillside, the system having a concrete abutment inset in the hillside but having an outwardly exposed lateral face, bearing pilings for the abutment, anchor rods and a deadman anchor further stabilizing the abutment, and a hollow cantilevered support pad tied to the exposed face of the abutment and extending horizontally over the hillside to constitute a support pad for the structure and define storage space, for example, for septic tank, utilities and storage purposes.

CANTILEVERED SUPPORT SYSTEM FOR STRUCTURES

An object of the invention is to provide a support system for houses and other structures which enables the use of land which has previously been unuseable due to steepness of terrain.

Another object of the invention is to provide a cantilevered support pad for supporting a structure in overhanging relation to a hill without requiring direct underpinnings.

A further object of the invention is to provide a support pad of the type described in the form of a structural shell to delineate subjacent space for storage and other purposes in relation to the structure.

Other objects and advantages of the invention will be apparent from the following description taken in conjunction with the drawing forming part of this specification, and in which:

FIG. 1 is a view in perspective of a structure and the structure support system of the invention;

FIG. 2 is a view in vertical cross section of the support system;

FIG. 3 is a view in front elevation of the support system; and

FIG. 4 is an enlarged detail view taken along lines 4-4 of FIG. 2.

Referring to the drawing, a structure 10 is shown supported in overhanging relation to hillside 12 by the support system of the invention. This system comprises an elongated concrete abutment 14, bearing pilings 16, deadman anchor 18, connector rods 20 interconnecting abutment 14 and anchor 18, and a tapered cantilever beam indicated generally at 22 secured by connector rods 24 to abutment 14. Beam 22 is in the form of a structural shell comprising upper and lower walls 26 and 28, inner and outer walls 30 and 32, diaphragm members 34 interconnecting these various walls, and bridging members 36 interconnecting the upper and lower walls 26 and 28 and adjacent diaphragm members 34. Diaphragm members 34 divide the interior of beam 22 into a pre-selected number of compartments for such as septic tank, utilities and storage usage. Preferably the diaphragm members 34 form the side members of individual modular units suitably dimensioned for transportation by trucks.

It will be appreciated that if the hillside earth were removed from all about the support system, except for the footings of the pilings 16, the structure 10 would still be stably supported by an adequate safety factor, the pilings 16 being sufficient in number and strength to support the weight of the whole system, including the structure, and to effectively resist the torque applied to abutment 14 by beam 22 and structure 10, and the anchor 18 and connectors 20 serving to apply an

off-setting counter-torque to the abutment 14. Of course, the presence of the earth, i.e. earthen enclosure means of the hillside in covering or supporting relation to the elements of the support system increases the potential resistance to movement of the support system, but the earth can be looked upon as furnishing the means for physical access to the otherwise stably supported structure.

It will be appreciated that the concrete pilings 16 constitute one species of support means for the abutment 14, another being bed-rock when available.

What is claimed is:

1. In combination, an abutment having upper, lower, rearward and forward surfaces, support means connected to and extending downwardly from the abutment, a deadman anchor disposed rearwardly of the abutment and connected thereto by connector rods, earthen enclosure means for the support means, connector rods, anchor and the rearward and lower surfaces of the abutment, said forward surface of the abutment being free of said enclosure means, and a platform attached to the forward surface of the abutment and extending therefrom.

2. The combination of claim 1, said forward surface of the abutment having at least a portion thereof which is inclined downwardly and rearwardly out of a vertical plane.

3. The combination of claim 1, said platform comprising a plurality of interconnected and disconnectable cell-like modular units.

4. The combination of claim 1, said platform having upper, lower, rearward and forward surfaces, the platform rearward surface being complementary to and in engagement with the abutment forward surface, the platform upper surface being substantially parallel to and level with the abutment upper surface, the platform lower surface being inclined upwardly and forwardly from the platform rearward surface to the platform forward surface.

5. The combination of claim 4, including a structure mounted upon and attached to the platform upper surface, said platform being substantially hollow and having internally disposed reinforcement and partitioning means defining at least in part service compartments for the structure.

6. The combination of claim 1, said platform being in the form of a substantially hollow structural shell attached to the forward surface of the abutment, a structure mounted upon and attached to the platform, said platform having internally disposed reinforcement and partitioning means defining at least in part service compartments for the structure.
